Primary Examiner — Anhdao Doan(57) **CLAIM**

The ornamental design for a glycaemic assessment test device, as shown and described.

DESCRIPTION

FIG. 1 is a front view of a glycaemic assessment test device showing my new design;

FIG. 2 is a perspective view thereof;

FIG. 3 is a left side view thereof; and,

FIG. 4 is a rear view thereof.

The parts shown as broken lines in FIGS. 1 and 2 represent either an actual perforation in the sheet which sits on top of the device casing, or is a dotted or hatched printed line.

1 Claim, 4 Drawing SheetsFIG 1.

FIG 2.

FIG 3.

FIG 4.
